(57) **CLAIM**

The ornamental design for an automatic screwfeeder, as shown and described.

DESCRIPTION

FIG. 1 is a side elevational view of an automatic screwfeeder according to the present invention;

FIG. 2 is an opposite side elevational view of the present invention;

FIG. 3 is a top elevational view of the present invention;

FIG. 4 is a bottom elevational view of the present invention; FIG. 5 is an enlarged front elevational view of the present invention; and,

FIG. 6 is an enlarged rear elevational view of the present invention.

All broken lines form no part of the claimed design.
